UNITED STATES PATENT OFFICE.

VINCENT NIZNANSKY, OF BETHLEHEM, PENNSYLVANIA.

HOLDER.

Application filed January 22, 1927. Serial No. 162,838.

This invention relates to improvements in holders and has particular reference to a holder for a writing instrumentality.

The primary object of the invention resides in a holder for insertion upon the finger of a human hand for holding a pencil, pen or brush in a writing position to relieve any fatigue on the part of a user.

Another object of the invention is to provide a holder of the kind mentioned which includes a ring member adapted to be worn on the index finger of a user and a removable clip associated therewith and which clip receives the pencil to be held. By reason of the clip being removable from the ring, it is possible for the user to wear the ring at all times as the same is designed to simulate a finger ring so as not to attract undue attention when worn as such.

20 A further object of the invention is the provision of a holder composed of two separable parts and which may be quickly assembled for use or disassembled when not in use.

25 A still further object is to provide a holder of the class mentioned which is simple in construction, inexpensive of manufacture and highly useful for the purpose intended.

With these and other objects in view, the 30 invention resides in certain novel construction and combination and arrangement of parts, the essential features of which are hereinafter fully described, are particularly pointed out in the appended claims, and 35 are illustrated in the accompanying drawing, in which:—

Figure 1 is a perspective view of my improved holder in assembled position upon the finger of a user.

40 Figure 2 is a horizontal sectional view therethrough.

Figure 3 is a perspective view of the holder in a separated condition.

Referring more particularly to the drawing, the reference numeral 10 designates my improved holder in its entirety and which includes an attaching means 11 and a pencil, pen or brush holder means 12. The attaching means 11 comprises an annular ring 13 having a flat surface or head 14 thereon similar to the well-known finger rings and which surfaces may have settings of jewels 15 therein or the initials of the owner may be inscribed thereon so as to resemble a signet ring. The rings may be constructed

of different sizes to fit the fore-finger or other fingers of the user, and may be of different materials depending upon the likes of the user and the price for which the article is to be sold. The flat surface 14 has a socket 16 provided centrally thereof and adjacent to the entrance there is provided spaced parallel resilient jaws 17 for normally restricting the entrance of the socket. The socket and the jaws constitute a female element for co-action with a male element provided on the holding means 12 now to be described.

The holding means 12 comprises a spring clip 18 of a size to receive and grip a particular writing instrument to be used. The back of the clip is provided with a headed stud 19 and which head is received in the socket 16 when the parts are in assembled position and is locked therein by the jaws or wires 17. As the head is inserted into the socket, the jaws 17 will yield to permit of the entrance of the head but when properly seated, the jaws engage beneath the head and prevent accidental separation of the parts.

In use, the user may constantly wear the ring 13 upon his finger for ornamental purposes and when writing or cleaning, the pencil, pen or brush is inserted into the clip 18 where it is held by the same and the clip connected with the ring 13 in a manner just explained. The ring is shifted down near the end of the finger to the position shown in Figure 1 of the drawing and the pencil adjusted to the proper position in the clip. It will therefore be noted that the holder supports the pencil at the desired angle when writing and eliminates the necessity of the user in tightly gripping the pencil. The fatigue caused by continuous writing is greatly relieved and the holder permits of a free and easy movement of the hand when writing thereby increasing the speed and improving the penmanship of the writer. At 100 rest intervals, the pencil may be released by the fingers and turned about its pivot formed by the socket and head to any desired position. The pivot point also allows the pencil to be adjusted radially with respect 105 to the attaching ring.

By constructing the holder of two separable parts, it is possible to employ a plurality of interchangeable clips in connection with a single ring to receive instruments 110

of different forms such as a pencil, pen or brush thereby making it unnecessary to have a different ring for each writing instrument to be used. The clips may be left on the writing instrument so as not to become lost when not in use.

What is claimed as new is:—

1. A holder of the class described comprising a ring member having a surface thereon for receiving an ornamentation, a spring clip, a female element provided in the surface of said ring member, and a male element provided on said spring clip for co-action with said female element for detachably connecting said clip with said ring member

and for permitting turning movement of the same with respect to each other.

2. A holder for writing instrumentalities comprising an annular ring member having a socket therein, yieldable jaws normally restricting the entrance to said socket, a spring clip, and a headed stud provided on said spring clip and insertible in said socket and engageable by said yieldable jaws for detachably connecting said clip with said annular ring member.

In testimony whereof I have affixed my signature.

VINCENT NIZNANSKY.
